(57) **CLAIM**

The ornamental design for a crate as shown and described.

DESCRIPTION

FIG. 1 is a perspective view of a crate showing our new design, in a closed configuration.

FIG. 2 is a top plan view thereof.

FIG. 3 is a front elevational view thereof.

FIG. 4 is a right side elevational view thereof.

FIG. 5 is a rear elevational view thereof.

FIG. 6 is a left side elevational view thereof.

FIG. 7 is a bottom plan view thereof.

FIG. 8 is a perspective view thereof, in an open configuration.

FIG. 9 is a top plan view thereof.

FIG. 10 is a front elevational view thereof.

FIG. 11 is a right side view thereof.

FIG. 12 is a rear elevational view thereof.

FIG. 13 is a left side elevational view thereof; and,

FIG. 14 is a bottom plan view thereof.

The broken lines shown in the drawings depict portions of the crate that form no part of the claimed design.

1 Claim, 12 Drawing Sheets
